Fig. 2.

Inventor:
Thomas F. Byron

By Dyerforth, Lee, Chittor & Wilcox, Attys.

UNITED STATES PATENT OFFICE.

THOMAS F. BYRON, OF CHICAGO, ILLINOIS.

CURTAIN-ROD HOLDER.

1,377,666.

Specification of Letters Patent. Patented May 10, 1921.

Application filed October 25, 1920. Serial No. 419,888.

To all whom it may concern:

Be it known that I, THOMAS F. BYRON, a citizen of the United States, residing at Chicago, in the county of Cook and State 5 of Illinois, have invented a new and useful Improvement in Curtain-Rod Holders, of which the following is a specification.

My invention relates more particularly to devices for securing curtain or drapery rods 10 in operative position, as for example at windows or at door openings in the wall between rooms; and my primary object is to provide a novel, simple and economical construction of holder which may be quickly, 15 and readily, secured in operative position at a door opening or window casing, and be readily removed therefrom. A further object is to provide a holder device which may be used in connection with supporting studs 20 of different sizes.

Referring to the accompanying drawings:

Figure 1 is a perspective view of one end 25 of a curtain rod, showing a portion of a curtain thereon, the rod being shown as provided at one end with my improved holder, with a headed stud, in connection with which it is adapted to be used shown as positioned in the holder. Fig. 2 is a view in vertical sectional elevation of the 30 frame of a window, or door opening showing a holder in accordance with my invention, positioned thereon for use.

The holder, in accordance with the preferred illustrated embodiment of the invention, is preferably formed of metal, the device which is represented at 3, being in the form of a cup presenting a cylindrical wall 4 and an end wall 5. The end wall 5 is so shaped as to incline outwardly in all directions from the axis of the device toward the cylindrical wall 4, in the direction of the open end of the device, as shown more particularly in Fig. 2, it being preferred that the outer marginal portion of the end wall 45 be so shaped as to be of rounded contour crosswise of the axis of the holder, as represented at 6. The end wall 5 is slotted to present the enlarged central opening 7 and the oppositely-extending elongated 50 openings 8 and 9, one of the last-referred-to openings being wider than the other thereof.

The device may be made in any desirable way, but preferably by forming it into the shape described and shown, by subjecting it 55 to a punching and shaping operation in a punch press, whereby the entire structure de-

scribed is integral being formed from a single sheet of metal.

The holder described is provided for co-operation with headed studs secured in the framework, as for example the window or door frame, in which the curtain rod is to be supported, and extending toward each other into a position to be engaged by the holders. One such stud, shown as a screw stud, is 60 represented at 10, this stud being secured in the frame represented at 11 and which may be one side of the frame of a window or a door, the stud being headed as represented at 12, with its head spaced from the 70 surface of the frame member 11 from which the stud projects.

It will be understood that there are two of the devices shown, one for each end of the curtain pole such as that represented at 75 13, the ends of the pole extending into the open socketed ends of the devices 3 one of which would be arranged at each end of the pole. To secure the pole in place in the window or door opening, the socket members 80 would be slipped over the headed ends of the studs 10, the heads 12 thereof passing inwardly into the socket members through the enlarged portions 7 of the slots, the operator then permitting the curtain with the 85 holder devices 3 thereon to lower, in which position the shank portions of the studs 10 would extend into the narrower portions of the slots in the devices 3, the parts being so proportioned and arranged as shown, 90 that when the holders 3 lower on the studs 10, these holders will be forced over into rigid engagement with the opposing surfaces of the framework 11, by reason of the camming action exerted by the inclination 95 of the end walls of the members 3 against the inner faces of the heads 12, as hereinbefore stated, the holder devices engaging the framework as stated, at their beaded portion 6. While by the arrangement shown 100 the curtain rod is firmly held in the desired position, it may be readily removed, if desired, from the opening in which it is located, by the operator forcing the curtain rod upwardly to move the devices 3 into a 105 position in which the enlarged portions 7 of the slots therein register with the heads 12.

In the particular arrangement shown the slotted portions 8 and 9 are of different 110 widths to adapt the holders for use in connection with studs of different sizes.

It will be noted from the foregoing that by reason of the formation of the holders as described, the curtain rod may be applied to the desired position in the window, door or other opening, with ease, as the operator, even though parts of the structure are obscured from view in this operation, may readily effect registration of the enlarged portions 7 of the slots, with the heads of 10 the studs 10.

While I have illustrated and described a particular construction embodying my invention, I do not wish to be understood as intending to limit it thereto, as the same may 15 be variously modified and altered without departing from the spirit of my invention.

What I claim as new and desire to secure by Letters Patent is:

1. A curtain-holder formed of a socket 20 member the end wall of which is slotted to receive a headed stud, with a portion of the end wall inclining outward toward the open end of said socket member.

2. A curtain-holder formed of a socket 25 member the end wall of which contains a

radially-disposed slot formed with an enlargement to receive the head of a stud, a portion of the said end wall inclining outward toward the open end of said socket member. 30

3. A curtain-holder formed of a socket-member comprising a wall portion of general cylindrical shape, with an end wall secured thereto, said end wall being slotted to receive a headed stud, with a portion of 35 the said end wall inclining outward toward the open end of said socket member.

4. A curtain-holder formed of a socket member the side wall of which is cylindrical, the end wall of said socket member being slotted to receive a headed stud, with a portion of the end wall inclining outward toward the open end of said socket member. 40

5. A curtain-holder formed of a socket member the end wall of which is slotted, 45 said slot being enlarged between its ends to receive the head of a stud, said end wall at its slotted portion inclining outward toward the open end of said socket member.

THOMAS F. BYRON.
